UNITED STATES PATENT OFFICE.

WALTER R. KAHNS, OF BROOKLYN, NEW YORK, ASSIGNOR TO J. H. WHITE MANUFACTURING COMPANY, OF BROOKLYN, NEW YORK, A CORPORATION OF NEW YORK.

EXTENSIBLE SUPPORT FOR ELECTRIC-LAMP SOCKETS.

Application filed March 4, 1922. Serial No. 541,234.

To all whom it may concern:

Be it known that I, WALTER R. KAHNS, a citizen of the United States, residing at the borough of Brooklyn, in the county of 5 Kings, city and State of New York, have invented an Improvement in Extensible Supports for Electric-Lamp Sockets, of which the following is a specification.

My invention relates to supports for lamp 10 sockets in electric lighting fixtures, and while applicable to fixtures of different construction, it is particularly designed for use in connection with electric candle fixtures in which the lamp socket is surrounded by a 15 jacket or tube resembling a candle, the socket being supported in the upper end of the candle tube to hold the lamp in the proper relative position to the tube; these candle cylinders being of different lengths, it is im- 20 portant that the socket supports be adjustable so that the socket may be held in the proper position according to the height of the tube.

Adjustable supports have heretofore been 25 made, but those in common use lack proper rigidity and are inclined to wobble, and the object of my present invention is not only to remedy this objectionable feature, but also to provide a support with a double adjust- 30 ment, so that the support may be lengthened or shortened either at its top or bottom, or both if desired.

The details of the invention are herein- 35 after particularly described.

In the accompanying drawing:—

Figure 1 is a perspective view of the as- 40 sembled support, in actual size.

Fig. 2 is an elevation of the upper mem- 45 ber detached, and in enlarged size.

Fig. 3 is an elevation of the lower bracket 50 detached, and enlarged.

Fig. 4 is an elevation of the connecting link detached, and enlarged.

Fig. 5 is a section taken on the broken 55 line 5—5 of Fig. 1, but in larger size, and

Fig. 6 is a side view of the upper mem- 60 ber showing a modified form for attachment to a lamp socket, this view being also of enlarged size.

Similar reference characters denote like 65 parts throughout the several figures.

Referring to the drawing, 10 denotes an angle bracket, its horizontal arm 11 being provided with a threaded stud 12, for at-

tachment to a pipe terminal, or other suitable means of support.

The longitudinal edges of the vertical arm 13, of the bracket 10 are bent over towards each other leaving a space 14, between them, and also a space between these overturned portions and the flat body portion of this arm.

15 denotes a member to be connected with a lamp socket. The longitudinal edges of this member are bent over towards each other in the same manner as are the edges of the bracket 10, above described, leaving a space 16, between them corresponding in width with the space 14 between the overturned edges of the bracket. This member 70 15, is preferably formed from a single piece of sheet metal, and bent to shape after being cut out. A recess 17 is cut in the upper end forming two spaced arms or projections 18 and 19 in the ends of which holes 20 are 75 provided. These arms 18 and 19, are then bent at right angles to the body of the member 15, and are to be secured to the base of the lamp socket by screws, bolts or other suitable means, thus connecting the member 80 15, to the lamp socket.

21, indicates a link for adjustably connecting the member 15 with the bracket 10. This link is formed from a strip of sheet metal. A depression is made in one side its entire 85 length, forming a central longitudinal groove 22, on that side, and a central longitudinal rib 23 on the opposite side, leaving a flat longitudinal edge 24 on either side of the groove and rib. This link 21 is of a 90 width and thickness at the outer edges to be passed between and under the overturned edges of the bracket 10, and member 15, and to be slidable in each, the longitudinal rib 23, projecting into the spaces between the 95 overturned edges of these members.

Adjacent each end of the link 21 there is provided a threaded hole 25, into each of which is screwed a binding screw 26, for clamping the link to the bracket 10 and member 15, in any position to which it may be adjusted, it being obvious that upon turning down the screws 26, their ends will press against the flat body portions of the bracket or member 15, thereby forcing the flat longitudinal edges of the link against the overturned edges of such member or members, tightly binding the parts together, which of

course may be instantly released when desired, by turning the screw or screws in the opposite direction.

As a means for preventing the accidental withdrawal of the link from the member 15, I make a small central indenture in one side of the member 15, adjacent its lower end forming a projection 27, on the opposite side which projects into the longitudinal groove 22, and with which the binding screw in the upper end of the link will contact if drawn down sufficiently far, thus preventing the accidental separation of these parts. A similar projection 28 is formed in the upper end of the vertical arm of the bracket 10, for a similar purpose.

The formation of the upper end of the member 15 as shown in Fig. 1 and 2, is to provide for its connection to sockets now commonly in use in this class of lighting fixtures, but where it is desired to connect such member to lamp sockets provided at their lower ends with a threaded nipple, I provide the flanged or bent over upper end 25 of the member 15 with a threaded stud 29, to screw into the socket nipple, as illustrated in Fig. 6.

My invention provides against any possible wobble or lateral movement of the support, thereby holding the lamp socket steady in the position to which it may be adjusted. It also provides for the adjustment of the support either at the top or bottom, or both, which is of great importance, particularly 35 with candle tubes of extreme height, as the support may be lengthened to a much greater extent than has heretofore been possible. It will be readily seen, however, that for use with candle tubes of short or ordinary 40 height, the lower end of the connecting link may be tightly clamped within the bracket

in its lowermost position if desired, or it may even be permanently secured in such position.

I claim as my invention:

1. A support for an electric lamp socket, comprising three members, one member having its longitudinal edges over turned towards each other and provided at its upper end with means for attachment to the 50 socket, the second member having similarly overturned edges and provided at its bottom with a stud for connection with a pipe terminal, the third member being inserted slidably under the folded edges of the first 55 and second members, and means for clamping the same in that position.

2. A support for an electric lamp socket, comprising a member formed from a flat strip of metal, having its longitudinal edges 60 bent over towards each other leaving a space between them, and provided at its upper end with means for attachment to the socket, an angle bracket provided with a stud for connection with a pipe terminal 65 and having its vertical side edges bent over towards each other leaving a space between them, and a link formed from a flat strip of metal provided with a central longitudinal rib on one side and a corresponding 70 groove in its opposite side, said link passing under the bent over edges of said member and bracket and adjustably connecting the same, the rib on said link projecting into the spaces between said bent over edges of 75 the said member and bracket, and binding screws passing through a threaded hole in each end of said rib.

Signed by me this 27th day of February, 1922.

WALTER R. KAHNS.
